DUAL PIVOT TOGGLE MECHANISM FOR LOCKING AND RELEASING PIVOTED JAW WRENCH

Ernest A. von Seggern, Burbank, Calif.

Application June 14, 1954, Serial No. 436,330

8 Claims. (Cl. 81—84)

This invention relates to pliers of the self-locking type, and in particular to pliers which have a release mechanism by which they may be readily unlocked.

It is an object of the invention to provide a simple means by which self-locking pliers, when locked onto an object, may be released therefrom with a minimum force, which is much less than that required to initially lock the pliers.

Another object is to provide a release mechanism which does not involve the use of auxiliary levers or triggers to affect release but utilizes only the basic plier components.

A further object is to provide a release mechanism which is simple and does not readily deteriorate or get out of order.

Fig. 1 is a plan view of one illustrative embodiment of the pliers when in the open, unlocked position;

Fig. 2 is a sectional view of the release mechanism taken along the line 2—2 of Fig. 1;

Fig. 3 is a sectional view of the adjustable toggle joint taken along the line 3—3 of Fig. 1;

Fig. 4 is a plan view of the pliers of Fig. 1 shown in the closed and locked position; and

Fig. 5 is a plan view of the pliers of Fig. 1 shown when the locking pressure on the plier jaws has been released, but the jaws have not yet opened.

In the conventional self-locking pliers an over-center toggle joint is employed to hold the pliers closed when locked on an object. The force required to release the toggle joint is equal to that required to close the toggle. In the present invention, two toggle joints are arranged in series, one being used for locking the pliers in the conventional manner, and one, having a different leverage ratio, being used to unlock the pliers.

The pliers have a main body 11 to which is rigidly fixed a jaw 12, and a threaded adjusting screw 13 is mounted on the opposite end. A movable jaw 14 is pivoted at the pin point 15 in body 11 and said jaw has an operating handle 16 pivotally attached thereto at point 17. The handle 16 has a release link 18 located within and under said handle as shown in the sectional view of Fig. 2, and is pivotally joined thereto at point 19. A toggle link 20 is pivotally joined at point 21 to release link 18 and is held in pivotal engagement with screw 13 at the point 22.

In order to maintain engagement at point 22, a pair of raised knobs 23 (Fig. 3) are formed into the end of link 20 which retain said link inside the semi-circular section 24 of the body 11. This semi-circular section extends for a length along the body 11 at least equal to the length of the adjusting screw 13.

Toggle link 20 is located within and under the release link 18 as shown in the sectional view of Fig. 2 and has two stops 25 and 26 which engage the release link in its closed and open positions respectively. Release link 18 also has a stop 27 which engages the handle 16 when in the semi-released position of Fig. 5.

A spring 28 is hooked around the pivot pin 19 and a hook 29 in the main body 11, and holds the jaws 12 and 14 in an open position when the pliers are in released position (Fig. 1). It also holds handle 16 in closed relation to (in engagement with) link 18 and holds toggle link 20 in engagement with adjusting screw 13.

2

Operation of the pliers when closing on an object 30 is entirely conventional. In the open position (Fig. 1) the opening of the jaws is limited by stop 26 in engagement with link 18, which limits the separation of handle 16 from body 11, and also by the adjusting screw 13 which regulates the jaw opening independently of that caused by the handle motion. Screw 13 is adjusted so that when handle 16 is squeezed down as shown in Fig. 4, the object 30 is firmly gripped in jaws 12 and 14 in the usual manner. In this position said jaws are locked because toggle joint pivot 21 lies "over-center" with respect to toggle joints 17 and 22 as shown by dashed line 31 (Fig. 4). The amount of over-center travel is limited by stop 25 whose engagement with link 18 also limits the motion of handle 16.

In the closing and locking operation as shown by Figs. 1 and 4, the link 18 remains inside handle 16 and performs no function. Pivot joint 19 lies below joints 17 and 21 as shown by line 31 (Fig. 4) which makes it "over-center" also and acts as a stiff joint. The amount of over-center travel is limited by the engagement of tail 32 of link 18 with the under side of handle 16.

To release the pliers from object 30 pressure is applied to the under side of handle 16 as indicated by arrow 33. This causes handle 16 to separate and move away from release link 18 as shown in Fig. 5, leaving links 18 and 20 engaged to act together, in effect, as a single stiff link. It is seen that a line 34 (Fig. 5) drawn between pivot points 19 and 22 passes above pivot point 21, which puts it in an "over-center" relation and maintains stop 25 in engagement with link 18. The upward motion of handle 16 has however moved pivot 19 upward with respect to pivot 17 so that line 34 passes above pivot 17 and this toggle joint has been released. This permits a slight movement of pivot 17 toward pivot 22 which releases pressure of jaw 14 on object 30.

It is seen that the initial upward motion of handle 16 has released the main pressure on object 30 and has brought stop 27 into engagement with said handle. Further upward motion of handle 16 therefore carries link 18 with it, causing pivot 21 to pass above line 34 also to release that toggle joint. The spring 28 then pulls the assembly back into the position of Fig. 1 where stop 26 limits the opening of the jaws 12 and 14 and pivot 19 is pulled down relative to pivots 17 and 21 which places link 18 back inside handle 16.

In the conventional locking pliers, a considerable force is required to break toggle joint 21 when the pliers are firmly gripped on an object 30. In this invention, joint 21 is not broken initially, but pressure on said joint is first reduced by breaking a second toggle joint 19 on which handle 16 has a leverage about four times as great as it has on joint 21, pivot 19 being much closer to pivot 17 than pivot 21. This makes it very easy to cause the initial movement of handle 16, and when toggle joint 21 is finally broken, the pressure is so much reduced that it also opens easily. The total movement of handle 16 from the closed to the open position is no greater than in the conventional pliers, but the opening force is greatly reduced.

60 I claim:

1. In a wrench of the type described, comprising a stationary jaw and handle, a first pivot means supported by said handle at a distance from said jaw, and a movable jaw pivotally connected to said handle adjacent said stationary jaw and operative with said stationary jaw, said movable jaw including a second pivot means, an over-center toggle type jaw closing and releasing mechanism pivotally connected between said movable jaw and said handle at said first and second pivot means, said 65 mechanism comprising: a dual pivot toggle comprising three pivotally connected links, including a first link piv-

totally connected to one of said pivot means, a second link pivotally connected to said first link at a release toggle joint, over-center stop means for said release toggle joint, a third link pivotally connected to the other of said pivot means and to said second link at a locking toggle joint, over-center stop means for said locking toggle joint, and a movable handle fixed to one of said links pivoted at said release toggle joint, whereby closing pressure exerted on said movable handle reacts first on said release toggle joint to lock said joint in an over-center position and thence to react secondly through the then rigid first and second links to the locking toggle joint to move and lock said locking toggle joint in an over-center position and close said jaws, and opening pressure exerted on said movable handle reacts first on said release toggle joint to break the same from an over-center position and release said jaws.

2. In a wrench of the type described, comprising a stationary jaw and handle, a first pivot means supported by said handle at a distance from said jaw, said handle including a first pivot means, and a movable jaw pivotally connected to said handle adjacent said stationary jaw and operative with said stationary jaw, said movable jaw including a second pivot means, an over-center toggle type jaw closing and releasing mechanism pivotally connected between said movable jaw and said handle at said first and second pivot means, said mechanism comprising: a dual pivot toggle comprising three pivotally connected links, including a first link pivotally connected to one of said pivot means, a second link pivotally connected to said first link at a release toggle joint, over-center stop means for said release toggle joint, a third link pivotally connected to the other of said pivot means and to said second link at a locking toggle joint, over-center stop means for said locking toggle joint, and a movable handle fixed to said first link, whereby closing pressure exerted on said movable handle reacts first on said release toggle joint to lock said joint in an over-center position and thence to react secondly through the then rigid first and second links to the locking toggle joint to move and lock said locking toggle joint in an over-center position and close said jaws, and opening pressure exerted on said movable handle reacts first on said release toggle joint to break the same from an over-center position and release said jaws.

3. A combination as in claim 2 and with a spring connected to said release toggle in the region of said release toggle joint and to said stationary handle, to hold said wrench in a normally open position with said release toggle joint in an over-center locked position and said locking toggle joint in an unlocked position.

4. A combination as in claim 1 and with a second over-center stop means for said release toggle joint operative on the release side of dead center position of said joint, whereby opening pressure exerted on said movable handle reacts first to break said release toggle joint and to lock in an over-center position on said second stop means to react secondly through the then rigid first and second links to move and break said locking toggle joint from a locked over-center position to an open position and release said jaws fully.

5. A combination as in claim 1 and with a second over-center stop means for said locking toggle joint operative on the unlocked side of dead center position of said joint, whereby the opening motion of said toggle and the opening of said jaws is limited.

6. A combination as in claim 1 and with the length of at least one of said first and second links between said pivot points thereof less than the length of said third link between the pivot points thereof, whereby the force required to break the release toggle joint to an unlocked position becomes less than the force required to break the locking toggle joint.

7. In a wrench of the type described, comprising pivotally connected stationary and movable jaws, the sta-

tionary jaw being provided with a handle, an over-center toggle type jaw closing and releasing mechanism connected between the movable jaw and said handle, said mechanism comprising: a dual pivot toggle comprising three pivotally connected links, including a first link pivotally connected to said movable jaw, a second link pivotally connected to said first link at a release toggle joint, and a third link pivotally connected to said second link at a locking toggle joint, and also pivotally connected to said fixed handle, a movable handle fixed to said first link, said second link being engaged by said movable handle and moved bodily therewith during closing movement of said movable handle, whereby said first and second links are rigid with one another and locking toggle action occurs at said locking toggle joint with said third link functioning as the remaining link of the locking toggle, stop means limiting said action of said locking toggle when said locking toggle joint has moved to an over-center position, said release toggle joint being in an over-center position relative to a line intersecting the pivot axis of the connection between the jaw and first link and the pivot axis of the connection between the third link and the fixed handle when said locking toggle is in said over-center position, said second and third links remaining initially rigid relative to one another owing to said over-center position of said locking toggle joint as said movable handle is opened, whereby release toggle action occurs at said release toggle joint, with said first link functioning as the remaining link of the release toggle.

8. In a wrench of the type described, comprising pivotally connected stationary and movable jaws, the stationary jaw being provided with a handle, an over-center toggle type jaw closing and releasing mechanism connected between the movable jaw and said handle, said mechanism comprising: a movable handle pivotally connected to said movable jaw at a first pivot point, a first toggle link positioned on the inner side of said movable handle and pivotally connected thereto at a second point spaced rearwardly along said handle from said first pivot point, said handle being engageable with said first toggle link at a point spaced rearwardly from said second pivot point during closing movement of said movable handle, a second toggle link pivotally connected at one end to said first toggle link at a third pivot point and at its opposite end to said fixed handle at a fourth pivot point, said movable handle and said first toggle link when in engagement during said closing movement forming one arm of a locking over-center toggle, and said second link connected thereto at said third pivot point forming the other arm of said locking over-center toggle, stop means on said second link engageable with said first link to arrest said closing movement of said movable handle when said locking toggle has reached a predetermined over-center position, said second pivot point being substantially in alignment with said first and fourth pivot points when said locking toggle is in said over-center position, the portion of said movable handle between said first and second pivot points constituting one arm of a release toggle, and said first and second links constituting the other arm of said release toggle, with the toggle joint thereof at said second pivot point, said first and second links forming an initially rigid toggle arm during opening movement of said movable handle owing to said over-center position of said locking toggle, whereby release toggle action occurs at said second pivot point.
